CONNECTION MEANS FOR PHONOGRAPH PICKUPS

Walter J. Brown and Alfred L. W. Williams, Cleveland Heights, Ohio, assignors to The Brush Development Company, Cleveland, Ohio, a corporation of Ohio

Application October 30, 1944, Serial No. 561,137

7 Claims. (Cl. 179—100.41)

1

Our invention relates to the art of translating mechanical vibrations into electrical impulses. More particularly our invention relates to means for supporting a pickup cartridge for an electrical phonograph, and is a continuation-in-part of application Serial Number 378,463, now U. S. Patent No. 2,368,198 dated May 4, 1944.

Pickup arms for electrical phonographs are designed with two pivots or bearings to allow for movement in two directions. The first or vertical pivot or bearing allows the pickup arm to move horizontally with respect to the record being played and, as the pickup arm stylus follows the grooves of a disk record in toward the center of the record, it allows the entire pickup arm to move about the first pivot. The second or horizontal pivot or bearing is one on which the pickup arm turns or moves in an up and down direction such as when the stylus is taken off of the record or when irregularities in the record or turntable cause the pickup arm to move up and down with respect to the phonograph. In the design and manufacture of these pivots or bearings considerable care must be exercised to keep the amount of bearing play at a minimum. This is particularly true for arms designed for use with laterally cut records which depend for their operation on imparting a torsional vibration to a needle which in turn imparts a vibration to an electro-mechanical transducer. Bearing play in the horizontal and vertical bearings causes a certain amount of the needle vibration to be absorbed by the pickup arm in the form of a torsional vibration about a longitudinal axis parallel to the length of the arm and also in vibration about the vertical axis. These torsional vibrations in the pickup arm reduce the amount of stylus vibration which is transmitted from the undulations in the record to the electro-mechanical transducer and may introduce serious distortion in the wave form at low frequencies. As the frequency of the vibration in the stylus becomes higher and higher the distortion in the wave form introduced by the torsional vibration of the pickup arm becomes less and less due to the inertia of the pickup arm resisting the torsional vibration. The resistance to the torsional vibration in the pickup arm causes a higher percentage of the stylus vibration to pass to the electro-mechanical transducer and results in more efficient conversion of mechanical movement to electrical impulse. It is also desirable that the pickup arm be cushioned to prevent vibration produced by either the record, turntable motor, or any other source external of the stylus on the record from being transmitted to

2

the electro-mechanical transducer through the pickup arm.

In this invention we hingedly mount a phonograph pickup cartridge from a pivotably mounted pickup or tone arm in a manner to achieve all of the mentioned benefits and to reduce the unbalanced weight of the pickup arm which is supported on the phonograph record by means of the phonograph stylus.

10 It is an object of our invention to provide a mounting between a pickup arm and an electro-mechanical transducer which reduces the amount of vibration transmitted from the arm to the transducer and which resists torsional vibration

15 of the arm.

Another object is to provide a resilient connection between an electro-mechanical transducer and an arm.

20 A further object of our invention is to provide a connection between an electro-mechanical transducer and a supporting arm which resists torsional vibration of the transducer with respect to the said arm.

25 A still further object of our invention is to provide a resilient connection between an electro-mechanical transducer and a supporting arm or base which provides a damping action to prevent the undesired transfer of extraneous vibrations therebetween.

Another object of our invention is to resiliently 30 mount a transducer on a pickup arm in a manner to reduce the acceleration forces due to a warped phonograph record.

Other objects and a fuller understanding of 35 our invention may be had by referring to the following detailed description and claims, taken in conjunction with the following drawings in which:

Figure 1 is a sectional view of a portion of a 40 phonograph pickup arm and showing a pickup cartridge mounted on the arm.

Figure 2 is a cross-sectional view taken along line 2—2 of Figure 1, and

Figure 3 is a side elevation of a phonograph 45 pickup arm partly in section to show another method of mounting the pickup cartridge.

Figure 4 is a view, partly in section, of another form of our invention.

Figure 5 is a sectional view of a modified form 50 of our invention.

With reference to Figures 1 and 2 there is shown a form of our invention in which a transducer unit 55 is suspended from a pickup arm 10 by means of a resilient hinge 56 placed between the transducer 55 and the pickup arm 10. As the 55 stylus 61 follows vertical movements of an uneven

turntable or warped record the transducer unit 55 pivots about the hinge 56 and very little if any acceleration in a vertical direction is imparted to the pickup arm 10. By thus reducing inertia forces the stylus pressure on the record may be reduced and maintained more evenly thereby increasing the life of the records and of the stylus. As in the embodiments illustrated in the parent application, Serial Number 378,463, now U. S. Patent No. 2,368,198 dated May 4, 1944, the resilient hinge 56 may be a metal spring, but we prefer a block of rubber such as sponge rubber or the like as, in addition to the resilient property, it also has the property of effecting a damping action for reducing the transmission of vibration between the pickup arm 10 and the transducer unit 55. Fairly stiff sponge rubber blocks may be used to achieve these damping and flexing actions.

The transducer unit 55 is connected to the resilient hinge 56 by means of rivets or screws 57 and the resilient hinge 56 is connected by means of the rivets or screws 58 to a web 59 depending from the head 60 of the pickup arm 10, thereby suspending the transducer unit 55 from the pickup arm head 60. The resilient hinge 56 may have a relatively high section modulus oriented in a direction to prevent torsional vibration of the transducer 55 with respect to the pickup arm 10 and the pickup arm head 60, and may have a relatively low section modulus in a direction to permit the transducer unit 55 to move vertically with respect to the pickup arm head to accommodate vertical irregularities in the turntable or record. The point of connection between the transducer unit 55 and the pickup arm head 60 is substantially at the midpoint of the transducer unit 55, but is sufficiently off-center that when the head 60 is lifted from a record the stylus 61 drops slightly with respect to the head 60. The stiffness and location of the hinge 56 may be varied to obtain the least pressure on the point of the stylus 61 which is commensurate with good reproduction. The stylus 61 is connected to a piezoelectric crystal unit 62 by means of a drive wire 63, and the crystal unit 62 includes leads which are connected to the shielded wire 37. The transducer unit 55 and its connection to the amplifiers (not shown) are more fully described in Patent Number 2,081,862, issued to A. L. W. Williams. It is to be understood, however, that any other kind of transducer mechanism such as a magnetic transducer may be used with our invention.

Figure 3 illustrates another embodiment of our invention in which the transducer unit 55 (crystal, magnetic, or the like) is connected to the pickup arm head 60 by means of a resilient hinge 64. One end of the hinge 64 is connected to the transducer unit by means of rivets or screws 57, and the other end of the hinge is connected to the pickup arm 10 by means of rivets or screws 58, thus supporting the cartridge 55 from the pickup arm 10. The hinge is positioned at the end of the transducer unit away from the stylus 61, and it may be found convenient to use a finger 65 connected to the end of the pickup arm head 60 to engage the stylus end of the transducer unit 55 to prevent the hinge 64 from bending too far when the pickup arm is lifted from the record which is being played.

Figure 3 also illustrates a hinge and stop construction adapted for use with either of the embodiments of our invention shown in Figures 1 and 3. We provide a vertical stop 66 to limit the

amount of downward arm motion, in addition to the horizontal stop 41 to limit the amount of lateral arm motion. The vertical stop 66 is connected to the bearing shaft 22 by means of a screw or rivet 67 and is rotatable in a horizontal plane as the pickup arm rotates. The vertical stop 66 is not rotatable in a vertical plane and is adapted to limit the downward distance to which the pickup arm head 60 will move by engaging the underneath side of the pickup arm 10. The downward limit of the movement of the pickup arm head 60 is such that the head 60 is held by the stop 66 slightly above the record being played and to cause the stylus 61 of the transducer unit 55 to ride in the record groove with sufficient pressure for good reproduction. This pressure is represented by the force resulting from the effective weight of the transducer unit 55 and the elastic force exerted by the resilient hinge 64.

Figure 4 illustrates a further modification of our invention which is particularly useful if the pickup is to be used in an upside-down position, such, for example, as a pickup used to reproduce from the underneath side of a record. It is also useful if the record is to rotate about a horizontal axis and be reproduced by a pickup which is mounted sideways.

The cartridge 55 may be connected to the head 60 of the pickup arm 10 at a point which is substantially the balance point, and the spring 70 is positioned between the inside surface of the head portion 60 and the top-surface of the pickup cartridge. A molded ring 71 is provided on the head portion 60 and a similar ring 72 on the pickup cartridge to prevent slippage of the spring 70. The spring 70 exerts a biasing force which tends to push the stylus end of the cartridge 55 away from the head 60 to cause the stylus 61 to extend below the lower surface of the head 60. Thus, whether the pickup is in the position illustrated by Figure 1 or in the position shown by Figure 4, or in any intermediate position it will be operable.

It may be desirable to adjust the bias exerted by the spring 70. An example of where adjustment may be of value is when the cartridge 55 is connected to the head 60 at a location on the cartridge away from the balance point to cause the stylus end thereof to be slightly heavier than the other end. With this condition it would make a difference in the force exerted by the stylus against the record whether the pickup was operated in a normal or in an upside-down position. By utilizing a spring whose biasing force is adjustable the stylus force can be made uniform for normal or upside-down operation.

The biasing force of spring 70 is adjusted in the following manner. A pressure plate 74 is positioned between the spring 70 and the underneath side of the head 60, and a screw 75 extends through the top wall of the head 60. Turning the screw 75 in one direction causes the pressure plate to move toward the cartridge 55, thereby compressing the spring 70 and increasing the bias, and turning the screw 75 in the opposite direction relieves the bias.

This bias adjusting screw may extend through the top wall of the head 60 as shown, or it may extend through the cartridge 55. An advantage of having it extend through the cartridge 55 is that the bias of the spring 70 may be set when the pickup is put on the phonograph and the screw would then be out of sight and less apt to be tampered with.

By utilizing an adjustable bias device such as the illustrated spring and pressure plate arrangement it permits manufacturing one pickup for operation in normal, upside-down, or angular operation.

With the pickup constructions shown the stylus 61 will be biased into engagement with the phonograph record by the unbalanced weight of the transducer, or, in the device of Figure 4, by the unbalanced weight (if any) plus the spring bias. When playing a record the unbalanced weight of the pickup arm is substantially entirely supported by the vertical stop 66 which permits the pickup arm 40 to be lowered until the stylus 61 engages the record and until the transducer unit pivots slightly about the hinge by which it is connected to the pickup arm. The hinge, being resilient, exerts a force through the transducer cartridge to couple the stylus to the phonograph record, and this force reacts on the pickup arm. Thus to a small extent there is a slight amount of the weight of the pickup arm supported on the stylus. However, if the phonograph record is warped the vertical movement of the transducer cartridge caused by the unevenness results in a hinge action between the transducer and the pickup arm. The arm, therefore, is not moved to any great extent by the warped record and acceleration forces on the stylus are kept to a low amount.

Although we have described our invention with a certain degree of particularity, it is to be understood that the present disclosure has been made only by way of example and that numerous changes in the details of construction and the combination and arrangement of parts may be resorted to without departing from the spirit and scope of the invention as hereinafter claimed.

We claim as our invention:

1. A pickup device comprising a supporting arm, a complete transducer unit, and a single supporting means joining said transducer unit to the arm, said supporting means comprised of flexible rubber or the like and having a relatively high section modulus in a first direction and a relatively low section modulus in a second direction, means connecting one end of the flexible supporting means to said support, means connecting the other end of the flexible supporting means to said transducer unit in such a manner that the direction of said high section modulus is substantially perpendicular to and the direction of said low section modulus is substantially parallel to the longitudinal axis of said transducer unit whereby said supporting means resists torsional vibrations applied to the transducer unit and permits rotation of one end of the transducer unit with respect to said supporting arm.

2. A pickup device as set forth in claim 1, further characterized by said supporting means being substantially a solid block of flexible rubber or the like.

3. A pickup device as set forth in claim 1, further characterized by said supporting means

being connected to said transducer unit substantially at the center of longitudinal balance of said transducer unit.

4. A pickup device as set forth in claim 1 wherein said transducer unit has a stylus at one end thereof, further characterized by said supporting means being connected to the end of said transducer unit opposite said stylus end.

5. A pickup device comprising a supporting arm including at one end thereof an inverted hollow elongated cup-shaped head, a complete transducer unit, and supporting means joining said transducer unit to said head, said supporting means comprising a plate-like body of flexible rubber or the like, means connecting one end of the flexible supporting means to an inside wall portion of said head with the smallest dimension of said plate-like body in a direction substantially parallel to the longitudinal axis of said transducer unit, means connecting the other end of said flexible supporting means to said transducer unit whereby said supporting means resists torsional vibrations applied to said transducer unit and permits rotation of one end of the transducer unit with respect to said supporting arm.

6. A pickup device as set forth in claim 5, further characterized by said plate-like body being connected to a side wall portion of said inverted cup-shaped head and depending downwardly therefrom.

7. A pickup device as set forth in claim 5, further characterized by said plate-like body being connected to the bottom wall portion of said inverted cup-shaped head and depending downwardly therefrom free from engagement with the side walls of said head.
